COMBINATION HUNTER'S UTILITY TOOL

William A. Uttz, Fort Worth, Tex.

Application March 3, 1951, Serial No. 14,370

Term of patent 7 years

(Cl. D31—4)

To all whom it may concern:

Be it known that I, William A. Uttz, a citizen of the United States of America, residing at Fort Worth, in the county of Tarrant and State of Texas, have invented a new, original, and ornamental Design for a Combination Hunter's Utility Tool, of which the following is a specification, reference being had to the accompanying drawing, forming part thereof.

Fig. 1 is a top plan view of a combination hunter's utility tool, showing my new design;

Fig. 2 is a bottom plan view thereof;

Fig. 3 is a side elevational view thereof; and

Fig. 4 is a front elevational view thereof.

I claim:

The ornamental design for a combination hunter's utility tool, substantially as shown.

WILLIAM A. UTTZ.
